CLAIM

The ornamental design for a handle for shaving apparatus, as
shown and described.

DESCRIPTION

FIG. 1 is a top and rear perspective view of a handle for
shaving apparatus showing my new design;

FIG. 2 is a bottom and front perspective view thereof;

FIG. 3 is a right side view thereof;

FIG. 4 is a left side view thereof;

FIG. 5 is a front view thereof;

FIG. 6 is a rear view thereof;

FIG. 7 is a top plan view thereof; and,

FIG. 8 is a bottom plan view thereof.

The broken line showing of the blade head is for illustrative
purposes only and forms no part of the claimed design.
